UNITED STATES PATENT OFFICE

96,462

DESIGN FOR A TEXTILE FABRIC OR
SIMILAR ARTICLE OF MANUFACTURE

John F. Gaul, Jr., Clifton, N. J., assignor to
Botany Worsted Mills, Passaic, N. J., a corpora-
tion of New Jersey

Application April 5, 1935, Serial No. 56,218

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, in which—

Fig. 1 shows an enlarged face view of a piece of textile fabric embodying one complete unit of my design, which unit is contained in regular succession over the surface of the fabric in the relation indicated.

Fig. 2 is a cross-section along lines 2—2 of Fig. 1.

The characteristic feature of the design resides in a series of bars arranged within a unit in the relation indicated in the drawing and standing out from the surface of the fabric, the individual bars comprising a plurality of threads, being a part of the weave of the fabric and lying adjacent one another resulting in single bars or stripes.

I claim:

The ornamental design for a textile fabric or similar article of manufacture substantially as shown and described.

JOHN F. GAUL, JR.
